UNITED STATES PATENT OFFICE.

JOSEPH J. ALLISON, OF NEW ORLEANS, LOUISIANA, ASSIGNOR TO RACHEL H. STULL
AND AUGUSTA MAZE, BOTH OF INDIANAPOLIS, INDIANA.

SHOULDER-STRAP RETAINER.

Application filed November 17, 1924. Serial No. 750,422.

To all whom it may concern:

Be it known that I, JOSEPH J. ALLISON, a citizen of the United States, residing at New Orleans, in the parish of Orleans and 5 State of Louisiana, have invented new and useful Improvements in Shoulder-Strap Retainers, of which the following is a specification.

This invention relates to a device for 10 fastening shoulder straps of undergarments to a dress or outer garment, the general object of the invention being to prevent the straps from slipping or falling over the shoulders of the wearer and to hold 15 them under portions of the outer garment so that they will be hidden from view.

This invention also consists in certain 20 other features of construction and in the combination and arrangement of the several parts, to be hereinafter fully described, illustrated in the accompanying drawings and specifically pointed out in the appended 25 claim.

In describing my invention in detail, reference will be had to the accompanying drawings wherein like characters denote 30 like or corresponding parts throughout the several views, and in which:—

Figure 1 is a view showing the invention in use.

Figure 2 is a view of one of the devices with the same partly open.

Figure 3 is a section on line 3—3 of Figure 2, with the device in closed position.

As shown in these views, each shoulder strap holder comprises a strip 1 of webbing or the like which is placed between a pair of strips 2 of ribbon or the like, safety pins 4 being fastened to the ends of the strips 1. A strip 5, formed from a continuation of one of the strips 2 or a separate piece, is fastened at one end of the device and is adapted to be detachably connected

with the other end of the device by the snap fastener parts 6.

A pair of devices is pinned to the dress or other garment, as shown in Figure 1, under the shoulder portions of the same by the pins 4 with the detachable part 5 facing downwardly. Then this part 5 is passed 50 under the shoulder strap A of the undergarment and the loose end fastened to the device by the snap fastener part 6. Thus the shoulder strap will pass under the main part of the device and above the strip 5 so that said shoulder strap A is fastened 55 to the garment and cannot slip over the shoulder of the wearer or ride up the shoulder. Thus the device will act to hold the shoulder of the undergarment in position and hidden from view by the outer garment.

It is thought from the foregoing description that the advantages and novel features of my invention will be readily apparent.

I desire it to be understood that I may make changes in the construction and in the combination and arrangement of the several parts, provided that such changes fall within the scope of the appended 70 claim.

What I claim is:—

A device of the class described comprising a strip of tape, a safety pin connected with each end of the strip, a strip of covering material looped around the first strip longitudinally to enclose the same and passing through the pins, an extension formed on the covering strip and a snap fastener for connecting the free end of the extension 75 with the device so that the shoulder strap of a garment can be held between this extension and the rest of the device.

In testimony whereof I affix my signature.

JOSEPH J. ALLISON.
